UNITED STATES PATENT OFFICE.

HARRY JACKSON GREEN, OF SEBRING, OHIO.

MANTLE-RING-FORMING MACHINE.

1,345,845.

Specification of Letters Patent.

Patented July 6, 1920.

Application filed March 6, 1920. Serial No. 363,814.

To all whom it may concern:

Be it known that I, HARRY JACKSON GREEN, a citizen of the United States, residing at Sebring, in the county of Mahoning and State of Ohio, have invented certain new and useful Improvements in Mantle-Ring-Forming Machines, of which the following is a specification.

This invention relates to molding apparatus, being designed chiefly for forming the rings or holders of gas mantles whereby they may be turned out in quantity at a minimum cost and without any appreciable loss by breakage.

The drawings illustrate a preferred embodiment of my invention. I desire it to be understood that I may make such changes in construction, combination and arrangement of parts, materials, dimensions, et cetera, as may prove expedient and fall within the scope of the appended claims.

Referring to the drawings hereto attached:—

Figure 1 is a view in elevation, parts being broken away and parts in section, of a machine particularly constructed for demonstrating the application of the invention, the actuating means being omitted.

Fig. 2 is a top plan view of the machine, parts being broken away and parts being in section on the line 2—2 of Fig. 1.

Fig. 3 is a sectional detail on the line 3—3 of Fig. 2.

Corresponding and like parts are referred to in the following description and indicated in the several views of the drawings by like reference characters.

The machine embodies a suitable framework which, as shown comprises an upper plate 1 and a lower plate 2, and suitable tie rods or bolts 3. A plate 4 is placed upon the plate 1 and is secured thereto by the fastening means 3. The plate 4 is recessed in its under side and constitutes a casing for receiving certain parts of the machine which will be described more in detail hereinafter. A vertical opening is formed centrally in the plates 1 and 2 and is adapted to receive the working parts of the complementary dies.

A punch 5 is disposed above the plate or casing 4 and its lower portion is adapted to enter the casing and constitutes the main die, which forms the upper part of the mantle ring or holder. As shown most clearly in Figs. 1 and 3, the head provided as a part

of the punch 5 is stepped and otherwise formed to engage the casing and limit the downward movement of the punch. A recess 6 is formed centrally in the lower face of the punch and is adapted to receive the upper end of the mandrel 7 or a part applied thereto. The punch 5 is adapted to have a vertical movement imparted thereto and is mounted so as to move in a predetermined path. Any suitable treadle mechanism may be employed for operating the punch and as such mechanism is well understood in the art and constitutes no part of the present invention it is not deemed necessary to illustrate or refer to the same in detail. The mandrel 7 is secured at its lower end to the plate 2 and occupies a central position and is of a length so that its upper end extends through the top plate 1 and projects into the recessed portion of the plate or casing 4. The mandrel is progressively reduced in its length forming a plurality of annular shoulders 8, 9, and 10 which constitute stops to limit the downward movement of certain parts. The mandrel is in line with the punch. A sleeve 11 is loosely mounted upon the upper portion of the mandrel above the shoulder 8 and is limited in its downward movement by said shoulder. The lower end of the sleeve 11 is formed with an outer annular enlargement 12 which performs a dual function as will appear more fully hereinafter. The sleeve 11 extends beyond the shoulder 9 of the mandrel and enters the opening formed centrally of the top plate 1. A tip 13 is fitted to the upper end of the sleeve 11 and constitutes a renewable section thereof. The tip 13 receives the wear and is adapted to be replaced when worn or otherwise rendered unfit for further effective service, thereby obviating the necessity for providing a new sleeve which would result, if the part 13 were formed as a part of the sleeve 11 instead of separately therefrom. The upper and lower portions of the tip 13 are exteriorly reduced thereby resulting in the formation of an annular enlargement 14 which snugly fits within the opening of the plate 1 and comes flush with the outer side of the sleeve 11. The tip 13 consists of a short tubular section and its upper reduced portion is adapted to enter the lower face of the head of the punch as shown most clearly in Fig. 1. A collar 15 fits snugly within the

upper portion of the tip 13 and is provided at its lower end with an inner shoulder 16 which snugly embraces the upper end of the mandrel above the shoulder 10 which latter limits the downward movement of the collar. The collar 15 has a limited vertical movement. A cap 17 secured to the upper end of the mandrel 7 limits the upward movement of the collar 15, and this cap is 5 adapted to enter the recess 6 of the punch. The collar 15 forms the inside legs of the mantle ring or holder. An expansible helical spring 18 is mounted upon the upper portion of the mandrel, comprised between the shoulders 9 and 10 and is supported 10 upon the shoulder 9 and engages the lower end of the collar 15 and normally tends to press said collar upward into engagement with the lower end of the cap 17. An expansible helical spring 19 is mounted upon 15 the lower portion of the mandrel and rests upon the bottom plate 2 and normally exerts an upward pressure on the sleeve 11.

Slides 20, two in number are disposed 20 upon opposite sides of the upper portion of the mandrel and are located in the recess of the plate or casing 4. The slides 20 are adapted to have a lateral movement imparted thereto. The mold space 21 is 25 formed between the inner edges of the slides 20, the outer side of the tip 13, the lower end of the punch and shouldered portions of the tip 13 and slides 20 all as indicated most clearly in Fig. 1. The outer edges 30 of the slides 20 are beveled from opposite sides. As a result of having the outer edges of the slides 20 beveled from opposite sides, they present a V-form. The upper beveled portions 22 constitute cam surfaces whereby 35 the slides are positively moved inwardly.

The mechanism for positively operating the slides 20 in both directions comprises vertically disposed rods or bars 23, which are adapted to operate through openings 40 formed in the top and bottom plates 1 and 2. A yoke 24 connects the lower ends of the bars 23 and this yoke is adapted to be connected with a suitable treadle mechanism, not shown, whereby the bars 23 are 45 moved vertically. The upper ends of the rods or bars 23 are adapted to enter the recessed portion of the plate or casing 4. Recesses 25 are formed in the inner sides of the upper ends of the bars 23 and these recesses correspond with the tapered outline 50 of the outer edges of the slides 20. The upper walls 26 of the recesses 25 incline in conformity to the inclined or beveled edges 22 of the slides. When the bars 23 are at 55 the limit of their upward movement, the outer beveled edges of the slides 20 enter the recesses 25 and said slides occupy a position at the limit of their outward movement. When the bars 23 are at the limit of their 60 downward movement the upper portions 65

thereof, above the recesses 25 engage the outer edges of the slides 20 and hold the latter at the limit of their inward movement. At this time the mandrel in the mold space 21 is subjected to pressure by downward movement of the punch or die 5. The slides 20 are moved apart by means of companion bars 27 which are secured to opposite sides of the rods or bars 23. The bars 27 extend along opposite sides of the sleeve 11 and 70 are formed centrally with a vertical extension 28 which is tapered at its upper end. The tapered ends of the vertical extensions 28 are adapted to pass upwardly between the inner edges of the slides 20 and press the same apart when the bars 23 are moved upwardly. The parts are so disposed that when the inclined walls 26 of the recesses 25 clear the beveled or inclined edges 22 of the slides, the tapered ends of the projections 28 enter the space formed between the inner edges of the slides 20 so that 75 as the bars 23 continue to move upwardly, the slides 20 ride upon the inclined edges of the tapered ends of the extensions 28 and are moved outwardly thereby, the outer tapered portions of the slides entering the recesses 25. When the bars 23 are moved downward the tapered ends of the projections 28 are withdrawn from between the slides 20 and at the same time the slides are moved inward by the inclined walls 26 riding upon the inclined edges 22. The lower portions of the bars 23 are threaded 80 and receive nuts 29 and 29^a whereby provision is had for properly adjusting the bars 23 so as to operate properly. Stops 30 are mounted upon the bottom plate 2 and consist of sleeves through which the bars 23 pass. When the bars 23 are at the limit of 85 their downward movement, the nuts 29 come in contact with the upper ends of the sleeves 30.

When the plunger or die 5 is at the limit of its downward movement, the collar 15 is 90 in contact with the shoulder 10 and the sleeve 11 is in contact with the shoulder 8, both springs 18 and 19 being compressed. When the plunger or die 5 is elevated the collar 15 and the sleeve 11 are pressed upwardly by the respective springs 18 and 19. When the plunger is elevated the material is supplied to the mold. Downward movement of the plunger compresses the material in the mold. When the plunger is elevated 95 and the bars 23 move upwardly the slides 20 are pressed laterally apart, thereby releasing the article which is moved upwardly by the combined action of the sleeve 11 and collar 15 as will be readily understood.

Having thus fully described my invention what I claim as new and desire to secure by Letters Patent, is:—

1. In a molding apparatus of the character specified, a mandrel, a collar mounted on 100

- the mandrel and having a limited movement thereon, a sleeve encircling the mandrel and collar, and a die co-acting with the mandrel and collar and adapted to move the latter in 5 one direction.
2. In molding apparatus of the character specified, a mandrel, a collar mounted on the mandrel and having a limited movement, a spring on the mandrel for moving 10 the collar outwardly, a sleeve encircling the collar and spring, and a plunger co-acting with the mandrel and collar to move the latter against the tension of the spring.
3. In molding apparatus of the character specified, a mandrel, a sleeve mounted on the mandrel and having a limited movement, and a renewable tip forming in effect 15 a part of the sleeve.
4. In molding apparatus of the character specified, a mandrel having stepped portions, a collar mounted upon the mandrel, an expandible helical spring on the mandrel and normally pressing the collar upwardly, a sleeve mounted upon the mandrel and encircling the collar and the spring coöperating 20 with the collar, and a spring on the mandrel normally tending to press the sleeve upwardly.
5. In molding apparatus of the character specified, a mandrel comprising stepped portions, a cap secured to the end of the mandrel, a collar mounted on the upper end portion of the mandrel and having a limited movement, an expandible spring mounted on 25 the mandrel and normally pressing the collar upwardly, a sleeve on the mandrel inclosing the collar and the collar operating spring, and a spring on the mandrel normally pressing the sleeve upwardly.
6. In molding apparatus of the character specified, a stepped mandrel, a collar mounted on the mandrel and having a limited movement, an expandible helical spring mounted on the mandrel and normally exerting an upward pressure on the collar, a 30 sleeve on the mandrel, a renewable tip forming an extension of the sleeve and encircling the collar and the collar operating spring,
- and an expandible helical spring on the collar normally pressing the sleeve upwardly. 50
7. In molding apparatus of the character specified, laterally movable slides, longitudinally movable members having recesses to receive portions of the slides, parts of the slides and walls of the recesses being inclined to effect lateral movement of the slides. 55
8. In molding apparatus of the character specified, laterally movable slides, longitudinally movable members having recesses to receive portions of the slides, parts of the slides and walls of the recesses being inclined to effect lateral movement of the slides, and other members having a tapered portion to operate between the slides and move the same outwardly. 60
9. Molding apparatus of the character specified, comprising a mandrel, a punch in coöperative relation with the mandrel, slides at the sides of the mandrel and punch, longitudinally movable members having recesses to receive portions of the slides, corresponding parts of the slides and members being inclined to effect inward movement of the slides, and other members having tapered 70 portions to come between the slides to effect an outward movement thereof. 75
10. Molding apparatus of the character specified, comprising a lined mandrel and punch, laterally movable slides at the sides of the mandrel and punch, and having outer edge portions inclined, longitudinally movable members recessed to receive the outer edge portions of the slides, the recesses of the members having inclined walls to coöperate with the inclined edges of the slides, and other members movable with the longitudinally movable members and having tapered portions to come between the slides to press them apart. 80
